Primary Examiner — Rhea Shields

(57) **CLAIM**

The ornamental design for a part of an artificial lung ventilation apparatus, as shown and described.

DESCRIPTION

2.1 is a front view;
2.2 is a rear view;
2.3 is a side view;
2.4 is another side view;
2.5 is a top view;
2.6 is a bottom view; and
2.7 is a perspective view.
3.1 is a front view;
3.2 is a rear view;
3.3 is a side view;
3.4 is another side view;
3.5 is a top view;
3.6 is a bottom view; and
3.7 is a perspective view.

1 Claim, 14 Drawing Sheets
